[57] CLAIM

The ornamental design for helmet photodetector array, as shown.

DESCRIPTION

FIG. 1 is a left side elevational view of a helmet photodetector array showing our new design;

FIG. 2 is a bottom plan view;

FIG. 3 is a right side elevational view;

FIG. 4 is a top plan view;

FIG. 5 is a top, left side perspective view, the drawing being broken away for ease of illustration;

FIG. 6 is a front elevational view; and

FIG. 7 is a rear elevational view thereof.

FIG. 1

FIG. 2

FIG. 3

FIG. 4

FIG. 5

FIG. 6

FIG. 7
